UNITED STATES PATENT OFFICE.

WALTER WILSON, OF MERIDIAN, IDAHO, ASSIGNOR OF ONE-HALF TO RAYMOND BARNUM, OF NAMPA, IDAHO.

TOOL-HANDLE OILER.

1,349,931.

Specification of Letters Patent. Patented Aug. 17, 1920.

Application filed January 3, 1920. Serial No. 349,334.

To all whom it may concern:

Be it known that I, WALTER WILSON, a citizen of the United States, residing at Meridian, in the county of Ada and State of Idaho, have invented certain new and useful Improvements in Tool-Handle Oilers, of which the following is a specification.

This invention relates to an oiler for tool handles and the like and has the following 10 objects; to provide means for saturating a tool handle with oil; to provide a cylinder adapted to be placed in the end of tool handles; to provide means for attaching the cylindrical container in the end portions of 15 the handle so as not to cause the operator any inconvenience.

In the drawings:

Figure 1 is a fragmentary elevation of a tool handle showing the top portion in section equipped with my invention.

Fig. 2 is a top plan view of my invention.

Fig. 3 is a vertical section taken through the oil container and

Fig. 4 is a section taken on the line 4—4 25 of Fig. 3.

By referring to the accompanying drawings by numerals, it will be seen that 1 indicates the tool handle which is provided in its free end with the longitudinally extending cylindrical opening 2 so as to receive the oil containing cylinder 3. The cylinder 3 has the annular flange 4 situated upon its upper edge. This flange 4 is provided for resting upon the end of the handle 1 and is provided 30 with apertures to receive the screws 5 for firmly holding the cylinder within the opening 2. The cylinder 3 is closed at the bottom and is perforated with a plurality of openings 6. These openings 6 are comparatively small so as to allow the oil to slowly drip into the openings 2.

Adjacent the open end of the cylinder 3 there are situated threads for receiving the cap 7 which acts as a closure to the said open 45 end. By referring especially to Fig. 1 of the drawing it will be seen that the opening 2 is longer and has a greater diameter than the cylinder 3 so as to allow the oil to come into contact and saturate the interior portions of 50 the handle.

From the above description it will be seen that simple and efficient means have been

provided which may be used with a tool handle constructed of wood so as to saturate said handle with oil for preserving same. It 55 will also be seen that a device of this nature has been produced which will operate without causing any inconvenience to those who may be operating the tool handle.

Having thus described my invention what 60 I claim as new and desire Letters Patent upon is:—

1. In combination with a tool handle provided at its free end with a longitudinally extending cylindrical opening, a cylinder for 65 containing oil adapted to be inserted in said cylindrical opening so as to leave a space between said cylinder and the walls of said opening, said cylinder provided with a plurality of apertures in its side walls, means 70 for closing one end of said cylinder and means provided for attaching said cylinder to said tool handle.

2. In combination with a tool handle provided at its free end with a longitudinally extending cylindrical opening, a cylinder for containing oil provided with a plurality of apertures in its side walls adapted to be situated within said cylindrical opening so as to allow a space between said cylinder and the side walls of said cylindrical opening, a closure provided integrally with the side walls at the inserted end of said cylinder, a removable closure provided at the other end of said cylinder and means provided for attaching said cylinder to said handle. 80 85

3. In combination with a tool handle provided at its free end with a longitudinally extending cylindrical opening, a cylinder for containing oil adapted to be inserted within 90 said opening so as to allow a space between said cylinder and the side walls of said cylindrical openings, a screw threaded cap provided for closing one end of said cylinder, and means provided for attaching said cylinder to said handle. 95

4. In combination with a tool handle provided at its free end with a longitudinally extending cylindrical opening, a cylinder having a closed end for containing oil and provided with a plurality of apertures in its side wall and adapted to extend in said cylindrical opening so as to allow a space between said cylinder and the side walls of 100

said cylindrical opening, a screw threaded cap provided for closing the open end of said cylinder and an annular flange provided upon the open edge of said cylinder and adapted to extend at right angles thereto, and means provided for attaching said flange to the end of said handle.

In testimony whereof I affix my signature in presence of two witnesses.

WALTER WILSON.
